Attorney

UNITED STATES PATENT OFFICE.

VICTOR BERTON, OF NEW YORK, N. Y.

ORCHESTRAL APPARATUS.

Application filed April 24, 1925. Serial No. 25,659.

The present invention relates to orchestral apparatus, and more specifically to an improved cymbal beating apparatus for use by drummers in modern orchestras.

The primary object of the invention being to provide a device of this character which is intended to be placed upon the floor and operated by the left foot of the drummer, thus leaving the right foot of the performer free to operate the bass drum pedal.

A further object of the invention is to provide a device of this character which is portable,—in that the same is not connected with the bass drum or operating mechanism therefor in any manner; thus permitting of the same being freely movable into various positions in accordance with the desires of the performer.

A still further object of the invention is to provide a device of this character which is extremely simple and efficient in operation, and which may be manufactured at an extremely low cost.

Other objects and advantages of the invention will be apparent during the course of the following detailed description, taken in connection with the accompanying drawing, forming a part of this specification, and in which drawing:—

Figure 1 is a perspective view of the improved apparatus and showing the position of a performer's foot for operating the same; and,

Figure 2 is a central longitudinal section through the device showing the cymbals in a closed or striking position.

Referring to the drawing in detail, wherein for the purpose of illustration is shown but the preferred embodiment of the invention, and wherein similar reference characters designate corresponding parts throughout the views, the letters A and B may designate cymbals of ordinary construction, and which cymbals are adapted to be mounted in overlying relation to one another upon the operable supporting structure C.

Referring more specifically to the structure C, the same embodies a base section 5 and a treadle 6 hingedly connected together at their rear end portions as by a spring hinge 7 adapted for normally urging the free end of the treadle 6 upwardly above the free end of the base section 5 and into a position as shown in Figure 1. This spring hinge 7 is preferably of such construction as

to space the rear portions of the sections 5 and 6 a sufficient distance that when the treadle is pressed downwardly, the cymbal A will strike flat upon the cymbal B as shown in Figure 2. Such construction permits of the proper sounding of the cymbals when brought together.

The cymbals may be secured in proper position upon the confronting faces of the free end portions of the sections 5 and 6 as by bolts or other suitable fastening means 8.

A foot strap 9 is attached transversely of the treadle 6, and into which the performer may place the toe of his shoe, in a manner to prevent his foot from slipping off of the treadle and also permitting of the device being shifted about the floor surface into a position most convenient for operation of the device. A flexible link 10 connecting the sections 5 and 6, is intended for limiting the upward movement of the treadle 6, thus obviating the necessity of maintaining a constant pressure upon the treadle, and also preventing the treadle from flying upwardly when the performer removes his foot therefrom.

As will be apparent from the drawing, the base section 5 is formed relatively flat in order to prevent tilting of the device when being operated; and that the treadle 6 is formed with a reduced neck portion 11 at its forward or free end for affording a certain amount of spring yielding when the cymbals are struck together.

From the foregoing description of this invention it is apparent that an extremely simple and efficient orchestral apparatus of this character has been provided, which embodies many novel features over the present manner of sounding the cymbals.

Various minor changes may be made to the specific form of the invention herein shown and described, without departing from the spirit of the invention or the scope of the following claims.

I claim:

1. An orchestral apparatus comprising a base section for resting flat upon a floor surface, a cymbal mounted in a horizontal plane on the upper face of the base section adjacent one end thereof, a treadle hingedly connected at one end to the opposite end of the base section and adapted to overlie the base section, and a second cymbal mounted at the under face of the treadle for striking

engagement with the cymbal carried by the base section.

2. An orchestral apparatus of the class described, comprising a relatively flat base section adapted to loosely rest upon a floor surface and having a cymbal rigidly mounted in a horizontal plane on its upper surface adjacent the forward end thereof, a treadle section disposed in overlying relation to said base section and having a cymbal rigidly mounted on its under surface in overlying relation with said first mentioned cymbal, spring means hingedly connecting the rear portions of the base and treadle sections and adapted to normally urge the treadle section upwardly, and means connecting the base and treadle sections for limiting upward movement of the treadle section and downward movement of

the base section when the apparatus is lifted 20 from the floor.

3. An orchestral apparatus of the class described, comprising a floor engaging base section having a cymbal mounted on the upper surface thereof, a treadle hingedly 25 connected in overlying relation to said base section and having a cymbal mounted on its under surface in overlying relation to said first cymbal, and a foot strap secured to the treadle and extending transversely of the treadle for permitting of up and down swinging of the treadle about its hinged connection with the base section, upon the positioning of the foot of the performer upon the treadle with the toe beneath said 30 foot strap.

VICTOR BERTON.
